UNITED STATES PATENT OFFICE.

FREDERICK GEORGE CHAMBERLIN, OF FAITH, NORFOLK, ENGLAND.

DESIGN FOR A HIGH BOOT.

54,895.

Specification for Design.

Patented Apr. 20, 1920.

Application filed September 26, 1919. Serial No. 326,683. Term of patent 14 years.

To all whom it may concern:

Be it known that I, FREDERICK GEORGE CHAMBERLIN, a subject of the King of England, and residing at The Moyse, Horsham St. Faith, Norfolk, England, have invented a new, original, and ornamental Design for a High Boot, of which the following is a specification, reference being had to the accompanying drawing, forming part thereof, wherein—

Figures 1 and 2 are perspective front and rear views, respectively, which show a leg-

ing constituted by the upward extension of a boot and provided with a band carrying a strap and buckle, and which illustrate my new design.

I claim:

The ornamental design for a high boot, as shown.

FREDERICK GEORGE CHAMBERLIN.
